No. 897,357.

PATENTED SEPT. 1, 1908.

J. C. EDWARDS.

FILLING END HOLDER FOR WEFT REPLENISHING LOOMS.

APPLICATION FILED JAN. 28, 1908.

UNITED STATES PATENT OFFICE.

JOHN C. EDWARDS, OF BROOKLINE, MASSACHUSETTS, ASSIGNOR TO DRAPER COMPANY, OF HOPEDALE, MASSACHUSETTS, A CORPORATION OF MAINE.

FILLING-END HOLDER FOR WEFT-REPLENISHING LOOMS.

No. 897,357.

Specification of Letters Patent.

Patented Sept. 1, 1908.

Application filed January 28, 1908. Serial No. 413,120.

To all whom it may concern:

Be it known that I, JOHN C. EDWARDS, a citizen of the United States, and resident of Brookline, county of Norfolk, State of Massachusetts, have invented an Improvement in Filling-End Holders for Weft-Replenishing Looms, of which the following description, in connection with the accompanying drawing, is a specification, like letters on the drawing representing like parts.

This invention relates more particularly to the filling-feeder or hopper used in automatic filling-replenishing looms of the Northrop type, wherein the filling-carriers or bobbins are held in a movable feeder from which they are transferred one by one to the shuttle, as in United States Patent No. 529940 granted November 27, 1894 to J. H. Northrop.

The filling-ends are led from the tips of the bobbins around the edge of a bell-like disk and secured at their extremities by being wound about a central knob-like end-holder, and the accumulated waste filling must be removed therefrom from time to time, usually by cutting it off with a knife. The mass of waste must be cut off whether the end-holder is rigidly and permanently attached to the filling-feeder or removable therefrom, as it is tightly wound upon the shank of the end-holder and clings firmly to it.

My present invention has for its object the production of an end-holder so constructed and arranged that the waste may be readily removed or stripped without the use of a knife or cutting instrument and with a minimum expenditure of time.

The novel features of my invention will be fully described in the subjoined specification and particularly pointed out in the following claims.

Figure 1 is a vertical section of the usual supporting disk at the outer end of the filling-feeder, with one embodiment of my present invention applied thereto; Fig. 2 is a side elevation of the two-part filling-end holder, detached, the parts of the holder being separated; Fig. 3 is a right hand end elevation of the part of member of the end-holder which is permanently attached to the filling-feeder; Fig. 4 is a view similar to Fig. 1 of a modified form of my invention; Fig. 5 is a side elevation of the permanently attached member of the end-holder; Fig. 6 is a right-hand elevation thereof. Fig. 7 is a view similar to Fig.

4 of yet another modification to be described; Fig. 8 is a sectional view of the removable member detached.

Referring to Fig. 1 the stud 1 on which the filling-feeder is rotatably mounted, the surrounding sleeve 2 which connects the butt and tip supporting plates of the feeder, (not shown), and the bell-like disk 3 having its hub 4 attached by a set-screw 5 to the sleeve 2, are and may be all of usual construction in Northrop looms, the hub 4 having an outward extension 6, shown as slightly conical and socketed at 7. Upon the hub 1 mount the filling-end holder, herein comprising an expandible tubular member attached permanently to the hub, upon which member the filling-ends are wound to hold them in place, and a manually detachable expander adapted to normally expand and increase the diameter of the tubular member.

Referring to Figs. 1, 2 and 3 the permanently attached member is shown as a longitudinally slotted tube or barrel 8, made of sheet-metal of suitable resilience or springiness, and shaped at its inner end to form a tapered base 9 which fits over the hub 6 and is permanently secured thereto, as by screws 10. The tubular part or barrel 8 is preferably cylindrical when in its normal, or unexpanded condition, Fig. 2, at the left, the transversely segmental fingers 8^x which form the barrel receiving the extremities of the filling-ends, which are wound about the barrel when the latter is expanded.

The detachable member of the end-holder is shown as a tapered shank 11 having at its outer end an enlarged head or knob 12, the inner end being reduced at 13, to enter the socket 7 of the hub 6. When the shank is pushed into place it spreads or expands the barrel 8, increasing its effective diameter and giving it a conical shape, as shown in Fig. 1, and the part 13 of the shank by seating in the hub makes the end-holder rigid.

The filling-ends are wound upon the expanded barrel, and when a mass of waste has accumulated, as at 14, see dotted lines Fig. 1, and should be removed the weaver grasps the head 12 and withdraws the detachable member. Thereupon the spring fingers 8^x forming the barrel contract and resume their natural position, decreasing the diameter of the barrel so that the mass of waste 14 can be slipped off with a slight movement of the

hand. The detachable member is then replaced and the end-holder is again ready for use.

In order that the parts or members of the end-holder may not become accidentally separated by the vibration of the loom I have provided a simple locking device, by making an annular groove 15 in the shank near its head, and by inturning the outer ends of two of the spring fingers forming the barrel, as at 16, to enter the groove when the detachable member is in operative position, as in Fig. 1. The locking is automatic, and a slight, steady outward pull on the head of the detachable member unlocks it.

In the modification shown in Figs. 4, 5 and 6 the base 17 of the expandable barrel 18 is non-continuous, exposing the hub 6 for a portion of its surface, and a radial hole is made in the exposed part of the hub for a 20 slideable locking pin 19, Fig. 4, pressed inward by a light spring 20, the rounded inner end of the pin entering the socket 7 of the hub. The reduced end of the shank 21 of the expanding member has an annular groove 22 which is entered by the end of the pin when said member is in its operative position, locking it in place, as will be clearly understood. The inward push of the expanding member 25 will cause the locking device to act automatically, and an outward pull will release said member from control of the locking device when it is desired to strip off accumulated waste from the expandable member 18.

In Fig. 7 I have shown what is practically a reversal of the structures shown in Figs. 1 and 4, the expandable member 25 in this modification being the removable member of the end-holder, said member being made as a 40 longitudinally slotted tube, fastened at its outer end to a boss 26 on the knob-like head 27, the boss having a central lug 28, Fig. 8. The hub 6 has fixedly attached to it by a setscrew 29 the reduced end of an outwardly 45 tapered shank 30 having a socket in its outer end to receive the lug 28, and near the hub the shank is provided with an annular groove 31 into which snap the slightly inturned free ends 32 of the spring fingers forming the barrel 25. When the removable, expandable member, shown separately in Fig. 8, is pushed onto the shank 30 the barrel 25 is expanded, as shown in Fig. 7, the inturned ends 32 snapping into the groove 31 to lock the 55 members together. The filling-ends are wrapped around the expanded barrel, and when a mass of waste accumulates the removable member is detached by a quick outward pull on the head 27, the barrel 25 contracting as it is drawn off the shank, loosening the hold of the waste, which can be easily 60 stripped off by the fingers. The lug 28 by entering the socket in the outer end of the shank assists in providing a firm support for 65 the head 27.

It will be manifest that by the use of my invention no cutting of the waste is required to remove it, for the contraction of the expandable member upon removal of the expanding member leaves the mass of waste 70 loose upon the said expandable member, and it can be pushed or brushed off by a simple sweep of the hand.

Modifications or changes in details of construction may be made by those skilled in the art without departing from the spirit and scope of my invention as set forth in the appended claims.

Having fully described my invention, what I claim as new and desire to secure by Letters Patent is:—

1. In a filling-end holder, a tubular, expandable member and a member adapted to coöperate with and normally expand the tubular member, the filling-ends being wound thereupon, one of said members being detachable and the other member being permanently mounted on the filling-feeder, removal of the detachable member permitting the expandable member to contract within the mass of waste filling wound thereupon.

2. In a filling-end holder, a tubular, longitudinally slotted member, a coöoperating expanding member, to enlarge the effective diameter of the tubular member upon which the filling-ends are wound, one of said members being permanently attached to the filling-feeder, and means to prevent accidental separation of said members.

3. In a filling-end holder, a member having an expandable barrel, and a coöperating member having a tapering shank to enter and expand the barrel for the filling-ends to be wound thereupon, one of said members being adapted to be permanently attached to the filling-feeder, the barrel contracting upon separation from the shank to enable the filling waste on the barrel to be readily slipped off.

4. A rotatable filling-feeder having at its outer end a bell-like disk provided with an outwardly extended hub, a two-part filling-end holder comprising a resilient, expandable barrel attached to the hub and a detachable tapered shank having an enlarged head at its outer end, the shank when inserted in the barrel expanding the same in readiness to have the filling-ends wound upon it.

5. A rotatable filling-feeder having at its outer end a filling-end holder comprising an expandable, permanently attached sheet-metal tube, and a detachable tapering expander adapted to enter and expand the tube to have the filling-ends wound upon it, the tube contracting when the expander is detached therefrom, to release the mass of filling waste wound upon the tube.

6. In a filling-end holder, a tubular, expandable member, a member adapted to coöperate with and normally expand the tubular member, the filling-ends being wound

thereupon, one of said members being adapted to be permanently attached to the filling-feeder, separation of the two members permitting the tubular member to contract within the mass of waste filling wound thereupon, and a spring-lock to hold said members together and prevent accidental separation thereof.

7. A rotatable filling-feeder for looms having a socketed hub at its outer end, and a filling-end holder comprising a sheet-metal base attached permanently to the hub and having a series of outwardly extended resilient fingers forming an expansible barrel, a 15 detachable, tapering member having a head at its outer end and adapted to enter and expand the barrel, the inner end of said tapering member entering the socket in the hub, and means to automatically lock said members 20 from accidental separation.

8. A rotatable filling-feeder having at its outer end a bell-like disk provided with an outwardly extended hub, a two-part filling-end holder comprising a resilient, expansible 25 barrel, and a tapered shank adapted to be inserted in the barrel to expand the same in readiness for the filling-ends to be wound upon it, one of said parts being permanently attached to the hub and the other of said 30 parts being detachable.

9. A filling-end holder comprising a resilient barrel upon which the filling-ends are wound, and an expander for said barrel, one of said parts being mounted on the outer end 35 of a filling-feeder, manual separation of said parts permitting the barrel to contract in diameter.

10. A filling-end holder comprising a resilient barrel mounted on the outer end of the 40 filling-feeder, upon which barrel the filling-

ends are wound, and a manually detachable expander for said barrel, removal of the expander permitting the barrel to contract in diameter.

11. A filling-end holder for filling-feeders 45 of looms comprising an expansible member, and manually controlled means to effect expansion or contraction of said member, the filling-ends being wound upon the expansible member when it is expanded, the accumulated waste filling being loosened and rendered easily removable by contraction of such member.

12. In a filling-end holder for filling-feeders of looms, an expansible member upon which 55 when expanded the filling-ends are wound, and an expanding member to coöperate with said expansible member, manual separation of said members effecting contraction of the expansible member and leaving the mass of 60 waste filling loose thereupon.

13. A rotatable filling-feeder for looms having a hub at its outer end, combined with a separable filling-end holder comprising an expansible, tubular barrel and a tapered 65 shank adapted to enter and expand the barrel, and a knob-like head, one of said members being permanently secured to the hub and the other of said members to the head, the latter being located at the outer end of the 70 holder when the members thereof are in operative position.

In testimony whereof, I have signed my name to this specification, in the presence of two subscribing witnesses.

JOHN C. EDWARDS.
